UNITED STATES PATENT OFFICE

WILLIAM G. WOODRUFF, OF WAREHAM, MASSACHUSETTS, ASSIGNOR TO TREMONT NAIL COMPANY, OF WAREHAM, MASSACHUSETTS, A CORPORATION OF MASSACHUSETTS

NAIL

Application filed July 19, 1928. Serial No. 293,890.

This invention relates to improvements in nails.

One object of the invention is to provide a cut nail having its body or shank portion formed with one or a plurality of barbs or spurs adapted to bite into the wood or other material into which the nail is driven to anchor it against becoming loosened or pulling out.

10 Another object of the invention is to provide a cut nail having barbs or spurs projecting outwardly beyond the normal plane of its sides.

Another object of the invention is to provide 15 a cut nail having its body truncated or wedge-shaped in cross-section with barbs or spurs formed in two of its adjoining sides to project beyond the intermediate edge thereof.

20 Another object of the invention is to provide a cut nail which is more reliable and efficient in use than nails of the usual form, while being economical to produce in the process of manufacture.

25 Further objects of the improvement are set forth in the following specification which describes several embodiments of the invention as illustrated by the accompanying drawings. In the drawings:

30 Fig. 1 is a front elevation of a nail constructed according to one embodiment of the invention;

Fig. 2 is a rear view of the same;

Fig. 3 is a view of the right side of the nail 35 shown in Fig. 1;

Fig. 4 is an enlarged cross-sectional view of the body of the nail taken on line 4-4 of Fig. 1; and

40 Figs. 5 and 6 are views of a modified form of the nail showing another application of the invention thereto.

It has been a practice in manufacturing nails, and especially nails of the smaller sizes for use by artisans in producing fine cabinet-work, coach-work, or the like, to provide means for holding the nails in the work. For this purpose the nails are sometimes coated with cement or other sticky compounds; while in other instances the body of a wire nail is 45 formed with grooves, ridges or serrations.

According to the present invention the nails are preferably of the cut type, having the body truncated or wedge-shaped in cross-section with the side faces converging rearwardly from the front face. Along the edge 55 of the front face of the nail adjoining one side face I form a plurality of barbs or spurs. These barbs or spurs may be produced by the tools employed in cutting the nail from the sheet stock in the process of manufacture 60. Preferably, a portion of the barb extends beyond the normal plane of the front and side faces of the nail to provide a spur or tooth for projecting into the fibres of the wood or other material into which the nails are 65 driven.

In accordance with the form of construction of the invention shown in Figs. 1 to 4 of the accompanying drawings, the nail has an elongated body 11 that may taper gradually 70 downwardly from its head 12. The head 12 may be of ordinary construction, and have any desired size and shape.

The nails may be formed by cutting the sheet stock to provide a body 11 having a front face 13, rear face 14, and inclined side faces 15 and 16, respectively. The greater portion of the front face is preferably made wider than the rear face with the side faces 15 and 16 converging rearwardly therefrom 75 to form a body which is truncated or wedge-shaped in cross-section as shown most clearly in the enlarged view, Fig. 4.

That portion of the front face 13 contiguous to the side face 16 is formed with one or a plurality of barbs 17. Any number of these barbs may be provided on the body of the nail depending upon the purposes for which it is to be employed. Preferably, the barbs should extend from the entering end of the nail upwardly towards the head 12, being spaced at suitable intervals to provide a series of ratchet-like teeth along the edge of the tapered portion of the body 11.

The barbs 17 may be provided by forming notches 18 extending obliquely to the front face 13 of the body 11 into the side face 16, that is, across one corner of the body. The notches 18 may be triangular in shape, formed deepest in the front face 13 at a point adja-

cent the side face 16. The notches are preferably so shaped that the bottom face of each is inclined rearwardly from the plane of the front face 13 of the body 11, to form an abrupt shoulder or step 19 between adjacent notches.

In forming the notches 18 in the nail the metal is extruded or forced outwardly from its body 11 to cause the points 20 of the teeth 10 or spurs 17 to project beyond the normal plane of the faces 13 and 16. This method of construction constitutes an essential and important feature of the invention as providing that when the nail is driven into the work the barbs or spurs will cut cleanly through the wood or other material without rupturing the fibers. Consequently, the barbs will grip or bite into the wood to tenaciously resist any tendency for the nail to become loosened or pull out. On the other hand, the nail will have no tendency to split the wood or other material into which it is driven as is the case where the body of the nail is grooved or serrated across one or more faces or on all sides as in wire nails.

Figs. 5 and 6 illustrate a modified form of construction of the invention in which the nail 21 is provided with relatively long triangular-shaped barbs 22 projecting outwardly at one edge of its body 21. The face of the barb 22 is inclined outwardly at an angle to the face of the nail body from the entering end toward the head; this construction being the opposite to that shown in Figs. 1 to 3 in which the barbs are formed by depressions in the body. The form of construction shown in Figs. 1 to 3 is best adapted to large sized nails as the notching of the body assists in extruding the points of the barbs outwardly beyond the normal plane of its sides; but the modified form shown in Figs. 5 and 6 has been found preferable for small nails, brads or the like. As shown in Fig. 6, the direction of inclination of the barbs 22 is such that their tips or points lie outwardly beyond the normal plane of the faces of the nail body so as to provide wedge-shaped protuberances for penetrating the wood into which the nails are driven. When the invention is being applied to nails in the smaller sizes, a less number of barbs is provided as illustrated in Figs. 5 and 6 of the drawings, and in some cases a single barb may be used to good effect.

It will be observed from the above that the invention provides a nail having efficient means for gripping the material into which it is driven to resist the tendency for it to become loose or pull out. It has been demonstrated that nails of the present improved type have a much stronger grip or holding power, by actual test showing an increase of forty per cent. or more under normal working conditions.

While I have herein described and illustrated two preferred forms of construction

of the invention it is to be understood that other modifications may be made in the structure of the nail without departing from the spirit or scope of the invention.

Therefore, without limiting myself in this respect, I claim:

1. A cut nail having a body formed with flat sides meeting in relatively sharp longitudinal edges, with one side provided with indentations forming triangularly-shaped spurs having lateral shoulders extending across the side of the body at substantially right-angles to the edges thereof and with said shoulders terminating at one edge of the body in sharp points projecting laterally outward beyond the normal plane of its indented side and beyond its longitudinal edge.

2. A nail of the character specified having a head and an elongated body formed with flat sides meeting in longitudinal edges, one side of the body being indented to form triangularly-shaped spurs having their points directed downwardly from the head of the nail and formed at the top with lateral shoulders extending across the side of the body at substantially right-angles to its edges with the outer edges of the shoulders inclined at an angle to the normal plane of the side and terminating in sharp points which project beyond the adjacent edge of the body.

In testimony whereof I affix my signature.

WILLIAM G. WOODRUFF.
